UNITED STATES PATENT OFFICE.

HENRY V. HARTZ, OF CLEVELAND, OHIO.

IMPROVEMENT IN KNITTING-MACHINES.

Specification forming part of Letters Patent No. 123,100, dated January 30, 1872; antedated January 13, 1872.

To all whom it may concern:

Be it known that I, HENRY V. HARTZ, of Cleveland, in the county of Cuyahoga and State of Ohio, have invented a new and Improved Knitting-Machine; and I do hereby declare the following to be a full, clear, and exact description of the same, reference being had to the accompanying drawing making a part of this specification, in which—

Figure 1 is a plan view; Fig. 2, a side elevation of the yarn-guiding mechanism; Fig. 3, a perspective view of the loop-remover; Fig. 4, a front elevation of the registering apparatus; Fig. 5, a vertical plan of the bottom of the ellipse; Fig. 6, a perspective view of the device for making the "Prioche" stitch; Fig. 7, a front elevation of Fig. 5; Fig. 8, a sectional elevation of the means for shifting the hand-wheel; Fig. 9, a front elevation of the whole machine; Fig. 10, a side elevation of one of the half-rings; Fig. 11, a front elevation of the weight-clamp; Fig. 12, a sectional elevation of the same; and Fig. 13, a perspective view of the shaft F², its arms and teeth.

This invention relates to hand knitting-machines designed for family use, and embraces several improvements thereon, among which are, a device for widening, an apparatus for narrowing, a mechanism for making scarfs and other plain fabrics, an arrangement for preventing noise from the striking of the driving-pin against the ellipse that carries the yarn-guide, and a provision for throwing the driving-wheel out of gear with the serrated rings that bear the cams which operate the needles.

Referring to the drawing, A are a pair of rings of equal size, placed in a vertical position at an interval of six inches, more or less, and furnished with arms a, cast with the rings, and projecting from the upper edges thereof, from which arms extend lugs a¹, which are fastened to the frame B of the machine. The rings A have cog-teeth C on their inner sides. The teeth C gear with a driving cog-wheel, C¹, placed on a shaft, C², that rests in a tube, C³, Fig. 8, which is supported by an arm, C⁴, extending downward from one side of the frame B. On the opposite end of the shaft C² is the hand-wheel C⁵. A pin, c, placed at right angles to the axis of the shaft C² is supported in an arm, c¹, secured to the outside of the tube C³. The pin c passes through a slot in the

tube into a circumferential groove in the shaft, and is combined with a spiral spring, c², which keeps the pin in contact with the shaft. After pulling out the pin c the shaft C² can be moved endwise, so as to throw the wheel C¹ out of gear with the wheels C when the hand-wheel C⁵ is used for turning a well-known attachment carrying the spool, in order to wind yarn thereon. When the spool is filling with yarn it is a mere waste of power and material to operate the needles, and hence it is better to disconnect the wheels C and C¹, as before explained. The arms a aforesaid, together with other arms also springing from the rings A between the arms a, support the curved plates D placed parallel to the rings A, and inclined upward and inward from their outer edges, so as to be distant from each other at their inner edges half an inch, more or less. Grooves d are made cross-wise of the upper sides of the plate D, in which grooves lie the needles. Curved angle-bars D¹, concentric with the wheels C, are secured to the outer sides of the peripheries of the latter, at a suitable interval therefrom, by means of projections d² on the angle-bars, fastened to projections d³ on the wheels. At one end of each angle-bar D¹ is secured an inclined plate, D², extending above the adjacent plate D. The plates D² are secured to opposite ends of the bars D¹, and are so placed as just to clear the plates D as the bars revolve in opposite directions. To the inner side of each plate D² a supplemental plate, D³, is secured in such a manner as to be adjustable upward or downward. The lower edges of the plates D³ are serrated, so as to form the upper boundaries of cam-grooves that extend along the inner sides of the plates D², the apex of one of which grooves is seen at d⁴ Fig. 1. The projections at the bases of the needles enter these cam-grooves, and the needles are thereby operated as the plates D² move over the plates D. The plates D³ are riveted to rods d⁵, Fig. 1, the rivets passing through slots in the plates D². Screws projecting from the plates D² pass through slots near the lower ends of the rods d⁵. Arms d⁶, pivoted upon these screws, are provided with pins which extend into holes made for their reception in the plates D². Nuts d⁷, placed upon the screws, keep the parts aforesaid in place. By means of said arms and rods the

plates D³ may be moved so as either to widen the cam-grooves or make them narrower. The wider the cam-grooves the shorter are the loops which the needles pull down, and, consequently, the closer is the fabric produced. The narrower the cam-grooves, the more open is the fabric. From one of the wheels C projects, inwardly, an arm, e, Figs. 5 7, from the end of which a stud, bearing a roller, e¹, extends horizontally, entering an ellipse, E, Figs. 5 7 9, which is placed in a vertical position outside the adjacent wheel C, upon a horizontal rod, E¹, forming part of the frame B. The roller e¹, as the wheel to which it is attached revolves, communicates a reciprocating movement along the rod E¹ to the ellipse E. At the upper end of the latter is a frame, E², into which enters a pin, e², Figs. 2 9, that projects from an arm, E³, which springs from a tube, E⁴, that incloses a pin, e³, which projects horizontally outward from a bar, E⁵, Fig. 9, the same to which the rod E¹ is attached. The arm E³ bears at its upper extremity a rod, e⁴, Figs. 1, 2, 9, which arm is inclined nearly parallel with the adjacent plate D, above which it extends. At the upper end of the rod e⁴ is a plate, e⁵, through which is made a hole, e⁶. All the above-described mechanism, from and inclusive of the arm E³, is for the guidance of the yarn to the needles. The yarn passes from the spool through an eye, f, Fig. 1, attached to the side of the tube E⁴, thence by the side of the arm E³, through an orifice, f¹, in a curved bar, f², that extends back from the head of the arm E³, and is joined at its outer extremity to another part of said rod by a rail, f³. An elastic arm, f⁴, secured at its upper end to the rod e⁴, passes to one side of the curved bar f², and is bent in rear of the same. The yarn is passed over the bent part of the arm f⁴, and is by the latter pressed against the bar f² while passing through the orifice f¹. To one side of the rail f³ an elbow-lever, f⁵, is pivoted, and to this lever an arm, g, is attached. A prong, g¹, from the arm g, passes across the face of the bar f² outside of the yarn. The bights or turns in the yarn around the arm f⁴ and prong g¹ create a certain amount of friction. The arm g is of about the same length as the rod e⁴, and has an eye, g², at its upper extremity. To the outer end of the lever f⁵ is attached a slotted plate, g³, which, by means of a number of notches g⁴ made along one side of its slot g⁵, can be set higher or lower on the elbow-lever, as may be desired. A spiral spring, h, connects the lower end of the plate g³ with the arm E³. The yarn passing between the prong g¹ and the bar f² extends thence through the eye g², thence through the hole e⁶, and thence to the needles. The higher the plate g³ is set upon the lever f⁵ the greater is the tension of the spring h, and its consequent strain upon the yarn, which may be diminished by lowering the plate g³. The ellipse E is moved by the pressure of the roller e¹ upon the cages or frames E² F at the top and bottom of the ellipse. It vibrates the yarn-guiding mechanism back and forth, car-

rying the yarn between the two rows of needles. Pins h¹ extend from the inside of the ellipse one at the left of the cage E² and the other at the right of the cage F. But before the pin e¹ can strike the ellipse a projection, h², on the arm e comes in contact with the upper or lower pin h¹, as the case may be, and eases off the roller e¹, so to speak, preventing it from striking the ellipse forcibly and with a loud sound. In fact, the working of the roller in connection with the ellipse is noiseless. As shown in Fig. 9, the cage E² is divided by a vertical partition, h³, into two equal parts, each of which is sufficiently large to receive the pin e². When the yarn-guide is in motion, the pin e² being, as it were, passive with respect to the ellipse, and deriving all its movement therefrom, naturally always rises into that one of the spaces of the cage E² which is for the time being the rear one. Hence the yarn-guide, when in motion, must always be in line with the said rear space. This space is always in rear of the apex d⁴, or middle point, of either cam-groove. Therefore, as shown in Fig. 1, the delivery-hole e⁶ is always behind the middle of that one of the cam-grooves which is giving motion to the needles. The object of this arrangement is to render impossible the skipping of stitches by preventing the yarn from laying itself over any needle till after the latter, having cast its stitch, is drawn so far down by that portion of the cam-groove between itself and the apex d⁴, that the yarn can lay itself on the opened latch and so come, as the needle is subsequently depressed, between the latch and the hook, in order that the yarn may be caught by the hook during its descent and thereby pulled through the old loop. The widening of the tubular fabric for the purpose of forming the heel of a stocking is effected by inserting, as it were, a wedge with a curved head into one edge of the flattened tube, which wedge is double, one part being in each side of the fabric. Those needles which have knit that portion of the fabric which lies between the points of the wedge—or, in other words, the instep of the stocking—must be rendered inoperative when widening is to begin. For this purpose I employ half-rings F¹, Figs. 1, 9, 10, resting in grooves made lengthwise of the plate D above the needle. Prior to widening the blades h⁶ of the half-rings occupy these slots, said blades being of the same length as the plates D. Tongues h⁷ are attached at one end to the inner edges of the half-rings and are free at their other ends, which come next to the blades h⁶. Between the half-rings and their tongues are slots h⁴. The butt of the half-rings have racks h⁵ formed in their outer edges. F², Fig. 13, is a horizontal shaft mounted beneath the frame B at one side of the machine, and having at one end a hand-wheel, F³, Figs. 1 9 13. When the operator wishes to widen he moves the half-rings along the slots until the tongues h⁷ have run under as many needles on both sides as he wishes to render inoperative. The effect of thus running

the tongues under the needles is to raise the bottoms of the latter so high that, as the plates D^2 revolve, they pass under the needles instead of over them. The shaft F^2 is provided with arms k , both of which project from the shaft in the same plane and at the proper distance apart for the discharge of the function about to be described. The shaft is also provided with two sets of teeth, $k^1 k^2$, which sets are at the same distance apart lengthwise of the shaft as the racks h^5 . The middle part k^3 of the shaft is made four-sided, and this is for the purpose of furnishing a bearing for a flat spring, which extends from the frame B and, pressing on the part k^3 , prevents the shaft from turning at improper times. Attached to the outside of each angle-bar D^1 is a plate, k^4 , Fig. 9. These plates are constructed with lips k^5 , which form channels inclined from the outside toward the angle-bars. The plates k^4 are also constructed with lips $l l'$ next to the angle-bars, one in front and the other in rear of the lip k^5 . When not in use the shaft F^2 is turned so that its arms k point directly away from the machine, as shown at 1, in dotted lines, in Fig. 9. To bring it into play to begin the widening it is turned back into position shown in full lines in Fig. 9. The arms then extend past the outside of the angle-bars and lie directly in the path of the inclined lips k^5 . It should be understood that when one of the lips k^5 is in contact with its arm k the other lip k^5 is more than half a revolution distant from its arm k . Suppose the lip k^5 that is on the front side of the machine, the one shown in Fig. 19, to come into contact with its arm k . The effect is to move said arm and the shaft F^2 endwise a little, bringing the arm k in front of the lip l' and the lower tooth of the set k^1 into gear with the adjacent rack h^5 . The next moment the lip l' passes under and raises the outer end of the arm k , and this turns the shaft F^2 far enough to cause the tooth k^1 to move the half-ring F^1 with which it is in contact forward until its tongue h^5 passes under and renders inoperative another needle. When this takes place, instead of continuing the forward rotation of the hand-wheel C^5 , its motion should be reversed. The first effect of such reversal is to bring the inclined outer side of the lip l against the head of the arm k and, consequently, to move said arm and the shaft F^2 endwise in the opposite direction to its former movement, so as to throw the tooth k^1 out of gear with the rack h^5 . The next effect is to carry the plate e^5 backward past the same row of needles by which it had just traveled forward, which row, however, has been diminished to the extent of one needle by the moving forward, as above described, of the contiguous half-ring F^1 . Therefore the row of stitches made on that side as the plate e^5 moves backward will be shorter by one stitch than the last previous row. The next effect of the reversal of the hand-wheel C^5 is to cause the plate e^5 , after completing the backward movement just referred to, to move backward again past the

other row of needles until the lip k^5 on the back side of the machine comes up to the adjacent arm k , when movements occur similar to those described as taking place on the front side—that is to say, the shaft F^2 is moved endwise, the lower tooth k^2 thrown into gear with the contiguous rack h^5 , and the half-ring moved forward so as to render inoperative a needle on the back. Then the movement of the hand-wheel C^5 should be again reversed and another row of stitches shorter than the previous one by one stitch laid along the back side of the tube. The reductions in the lengths of the successive rows are continued until half the heel is knit—or, in other words, till the double wedge is complete. The heel is finished by the addition to the former of another double wedge knit in the reverse manner, the shortest row first, and from that to the longest row, which should be right angles with the upper side of the superior wedge.

This process is effected by simply turning the shaft F^2 downward till its arms k are in the position shown at 2 in broken lines, Fig. 9. By so doing the upper teeth of sets $k^1 k^2$, instead of the lower, will be successively thrown into gear with the racks h^5 , and the half rings D^1 will consequently be moved backward step by step as the backward and forward motions of the wheels continue releasing one of the inoperative needles at each movement until the second wedge is completed. Then the half rings should be moved backward to the positions shown in Fig. 9, and all the needles brought into play again.

The instrument shown in Fig. 3 is used for removing loops from the needles. It consists of a handle, F^3 , from the upper end of which extends a prong, l^4 , having on its extremity a hook, m^4 . To said prong is pivoted a lug, l^5 , entering a slot in the prong, and extending from a bar, m , whose point bears on the hook, being pressed thereon by a spring, m^1 . A brush, m^2 , is secured to the opposite side of the prong, l^4 . A hole, m^3 , is made through the prong l^4 at the base of the hook m^4 . The process in which the instrument is chiefly employed is that of narrowing, which is effected by moving the loop from the end needle of the row and laying it upon the next needle, which will then bear two loops. The manipulation consists in brushing back the latch from the hook of the needle by means of the brush m^2 , slipping the prong l^4 upon the needle-hook by means of the hole m^3 , drawing up the needle till the turned-down latch passes upward through the loop, depressing the bar m so as to raise its point clear of the hook m^4 , pressing the needle downward till the loop slides over the latch upon the prong l^4 , slipping the prong with the loop off from the needle, releasing the bar m so that it again presses on the hook m^4 , laying the loop upon the next hook, and finally pulling the prong from the loop without raising the bar m . When narrowing for the toe this must be done at both ends of the rows of needles; but when narrowing for the leg or foot

it has to be done only at one end. The angle-bars are each provided with a yielding piece, m^5 , Fig. 9, against which the bottoms of the needle from which the loop is to be taken should rest. This piece yields when the needle is pressed downward until the projection on the bottom of the needle slips under it, when by a spring the yielding piece is restored to its former position. In Figs. 1 and 6 n is an adjustable tooth, secured in a recess near the enlarged end of each angle-bar D^1 . When the tubular fabric is making these teeth are turned points downward, and are inoperative; but when solid fabrics are to be made with the "Prioche" stitch every other needle on each side should be pulled downward out of the fabric, so as to make it sufficiently loose, and the teeth n turned points upward. The result is that the teeth, as they are drawn past the bottoms of the needles, raise them to and leave them raised at such a height that as the needles of one side knit, their yarn is laid loosely over the needles of the other side continually, and consequently form a ribbed fabric, in whose ribs there alternates with each loop a simple curve of yarn, which is the proper description of the "Prioche" stitch, making very loose elastic goods suitable for scarfs, caps, &c.

In Figs. 11, 12, n^1 n^1 are a pair of jaws, jointed together at n^2 and combined with a spring, n^3 , whose tendency is to keep the jaws apart. To the inner side of one jaw is cast a catch, n^4 , and to a web, n^5 , on the other jaw is pivoted a latch, o . G, Fig. 9, is a horizontal bar secured to the inner side of one of the rings A, to which bar is jointed between lugs o^1 o^1 the inner end of a horizontal supporter, o^2 , which has a handle, o^3 , in the top of which is a notch for receiving a teat on one of the jointed arms n^1 . When turned outward at right angles with the bar G the end of the supporter lies vertically beneath the space between the two rows of needles. In this position it is used to support the jaws n^1 when open, a teat on the lower part of one of the jointed ends of the same resting in a notch in the supporter, and the curved upper ends placed between the two plates D and one at each side of the open space. The fabric consequently descends between the jaws. When the lower end of the fabric reaches the catch n^4 the jaws should be pressed together upon the fabric, the latch o turned into the catch n^4 , and the supporter o^2 turned away from beneath the jaws, leaving them hanging to the fabric and keeping the same taut.

In Figs. 4 9, q is a horizontal rod passing through an eye on the hanger H, and jointed at its outer end to a bar, q^1 , which is pivoted at q^2 to a plate, q^3 , shown also in Fig. 1, which is screwed to the frame B. The pivot q^2 also supports a dial-plate, q^6 , to whose back is secured a circular ratchet, q^4 , Fig. 4. To the bar q^1 is pivoted a pawl, q^5 , which engages with the ratchet q^4 beneath, and to the plate q^3 is pivoted a pawl, r , which engages with the same ratchet above and in an opposite direction. A spring, r^1 , keeps the pawl q^5 in position, and a counter-spring, r^2 , is combined with the arm q^1 . When the ellipse E moves toward the left it strikes the rod q , which vibrates the rod q^1 and turns the dial-plate q^3 a certain distance. As the ellipse moves toward the right the counter-spring r^2 draws the rod q^1 toward the perpendicular, but the pawl r prevents the dial-plate from turning backward; hence the dial-plate remains stationary after each movement until again moved forward. The dial-plate registers the number of rows that have been knit into the fabric, and the upper part of the rod q^1 serves as a pointer.

Having thus described my invention, what I claim as new, and desire to secure by Letters Patent, is—

1. The combination of the angle-bar D^1 , lips k^1 l^1 , shaft F^2 , arms k , teeth k^1 k^2 , half-rings F^1 , and racks h^5 , as specified.
2. The combination, with the two rows of needles, of the angle-bars D^1 D^1 and the adjustable teeth n n , as described.
3. The combination of the arm E^3 , sector f^2 f^3 , elbow-lever f^5 , rod g , prong g^1 , spring f^1 , slotted and notched plate g^3 , and spring h , as explained.
4. The combination of the ellipse E, pin h^1 , arm e , roller e^1 , and eccentric projection h^2 , as specified.
5. The combination of the cage E^2 , partition h^3 , pin e^2 , and arm E^3 , as described.
6. The combination of the adjustable supporter o^2 with the bar G, as explained.
7. The combination of the tube C^3 , grooved shaft C^2 , pin e , and spring c^2 , as specified.
8. The loop-remover, consisting of the prong t^4 provided with the hole m^3 and hook m^4 , the bar m , spring m^1 , and brush m^2 , as described.
9. The combination of the bars q^1 q^1 , dial q^6 , supporting-plate q^3 , ratchet q^4 , pawls q^5 and r , and spring r^2 , as set forth.
